LAMP SOCKET SWITCH USING EITHER
KEY OR PULL MECHANISM IN THE
SAME HOUSING

Harvey Hubbell, Long Hill, Conn.

Application January 27, 1949, Serial No. 73,131

1 Claim. (Cl. 200—51.15)

1

This invention relates to an electric lamp socket and switch therefor, and has for an object to provide a construction whereby either a key type or pull type switch mechanism may be used in the same housing or insulated body construction, so that with the same molded insulating parts of this housing or body the device may be assembled either as a key type switch or a pull type switch.

With the foregoing and other objects in view I have devised the construction illustrated in the accompanying drawings forming a part of this specification. It is, however, to be understood that the invention is not limited to the specific details of construction and arrangement shown but may embody various changes and modifications within the scope of the invention.

In these drawings:

Fig. 1 is a side elevation of the device removed from its enclosing shell and showing the pull type of operating means;

Fig. 2 is a similar view looking toward the opposite side thereof;

Fig. 3 is an exploded perspective view showing the various parts of the pull type switch mechanism;

Fig. 4 is an elevational view of the pull type switch mechanism assembled in the housing or body with one section of the housing or body removed, with parts broken away to more clearly show the construction, and with a portion of the screw shell contact in section;

Fig. 5 is a transverse section thereof substantially on line 5—5 of Fig. 4, showing the other section of the housing in place;

Fig. 6 is an end view of the pull chain guide looking from the left of Fig. 4;

Fig. 7 is an exploded view of certain of the switch elements of the pull type;

Fig. 8 is an end view of the spring support and operating pivots for the elements of Fig. 7;

Fig. 9 is a plan view of the movable switch element of the pull type;

Fig. 10 is a plan view of the operating element of the switch contact of Fig. 9;

Fig. 11 is a perspective view of the central socket contact and the connected stationary switch contact of the pull type of switch;

Fig. 12 is a perspective view of the other stationary switch contact of this type of switch;

Fig. 13 is an elevational view of the key type of switch assembled in this housing or body, with one section of the housing removed and the screw shells and contacts shown in section;

Fig. 14 is a transverse section thereof substantially on line 14 of Fig. 13;

2

Fig. 15 (Sheet 1 of the drawing) is an exploded perspective view showing the parts of the key type mechanism;

Fig. 16 is a perspective view of the central socket contact and the connected stationary switch contact of the key type mechanism;

Fig. 17 is a perspective view of the other stationary switch contact of the key type mechanism;

Fig. 18 is an exploded perspective view showing the movable switch element of the key type switch and the operating means therefor;

Fig. 19 is an end view of this movable key type switch element;

Fig. 20 is a face view of the inner side of one of the housing or body sections, with the switch elements omitted;

Fig. 21 is an elevation of the back or outer side of this section;

Fig. 22 is a similar view of the back or outer side of the other section;

Fig. 23 is a face view of the inner side of the housing or body section of Fig. 22, with the switch elements omitted;

Fig. 24 is a longitudinal section through the two sections of the housing or body when placed face to face, the plane of the section being substantially on the lines 24—24 of Figs. 20 and 22;

Fig. 25 is a similar section taken substantially on the plane of the lines 25—25 of Figs. 21 and 23, and

Fig. 26 is a longitudinal section through the two sections of the housing placed face to face taken substantially on the plane of the lines 26—26 of Figs. 20 and 22.

In electrical lamp sockets there are two types of switch mechanism commonly used for controlling the circuit to the lamp or other element, 40 as a plug-in type of connector plug in the socket, one being the so-called key type using a rigid insulated winged hand grip element for operating the rotary switch member, and the other the pull type, usually using a flexible pull chain for operating the rotary switch element. As these are different types of switches requiring a somewhat different arrangement of the switch, different shapes and arrangements of the housing or body members of insulating material are used for the two different types, requiring the use of two different sets of expensive dies for molding these housings or bodies of insulating material, and also requiring different and separate molding operations for these housings of the two types of switches. In the present construction, however,

the same housing or body is so formed that either

type of switch as desired can be mounted in this housing, thus requiring only one set of dies for molding this housing, and only one molding operation, and therefore only one type of housing issued for both types of switches. It is therefore not necessary to keep two different types of housings separated during manufacturing operations, as the same housing elements are used for the two types of switches. This greatly reduces the cost of manufacturing operations, as only one set of dies is required and the housings for both types of switches are the same.

In Figs. 20 to 26, the molded housing or body of molded insulating material is shown independently of the switch elements, and as stated above, either the pull type or key type switch may be assembled in this housing or body construction. This housing comprises two sections 1 and 2 of molded insulating material, such, for example, as "Bakelite" or similar molded plastics. The two sections are assembled face to face, as shown in Figs. 24 to 26, to enclose the various switch elements, although the elements are omitted in these figures to more clearly show the construction of the housing. In the outer side wall or surface of each section there is provided a recess to receive one of the binding post plates for connecting the lead wires from the house circuit to the switch and socket. In section 1 this recess is shown at 3, and in section 2 it is shown at 4, this latter recess being extended through one end of this section. On their inner sides the sections are provided with various recesses to receive and mount the various switch elements. Section 1 is provided with an upright elongated recess 5 to which leads a semicircular guide passage 6 through the side wall of the housing, and at the opposite side of the recess 5 is a T-shaped recess 7. Beyond this recess is a generally circular recess 8 provided with inclined stepped surfaces 9, 10, 11 and 12, each ending in a stepped shoulder 13. At the center of this circular recess is a raised boss 14 surrounding a central opening 15 leading through the wall of the housing to a recess 16 in its outer surface. At the upper side of this circular recess is another recess 17 from which leads an opening 18 to the recess 3 in the outer surface of this section. At its lower end the section is provided with a slot 19 leading through this lower end to the lower part of the circular recess 8, and adjacent this lower end this section is provided with a transverse opening 20 leading through the wall of the section to a recess 21 in the outer surface thereof. This latter recess opens through the lower end wall of the section.

The other section 2 is provided with a recess 5a of the same size and complementary to the recess 5 of section 1, and leading to this recess through the wall of the section is a semicircular passage 6a complementary to the passage 6 of section 1, and on the opposite side of the recess 5a is a T-shaped recess 7a complementary to the recess 7 of section 1. When the two sections are assembled, as shown in Figs. 24 to 26, these three recesses and passages are in alignment and arranged face to face, so that together the recesses form compartments or recesses in the two sections, and the two semicircular passages 6 and 6a form a circular guide or passage to the interior of the housing. The section 2 is also provided with a recess 22 leading from the bottom of which is a further noncircular recess 23 from which leads an opening 24 through the wall of the section, for a purpose presently to be described, and 75

at one edge of the recess 22 is a deeper recess 25 to reduce the amount of material required for molding the section. In the lower end wall is a slot 19a leading through this wall to the recess 5 22 and arranged to be complementary to and in alignment with the slot 19 of section 1 when the two sections are assembled. Both sections are formed with a stepped recess 26 and 26a at one side of the passage or guides 6 and 6a and communicating with one end of the recesses 5 and 5a to form aligned shoulders 27 and 27a when the sections are assembled. At the opposite side of the recesses 5 and 5a, they are each provided with an upstanding lug 28 for a purpose presently to be described. Section 2 is also provided adjacent its lower end with a transverse opening 20a passing through the wall of the section and into the recess 4, and this opening is in alignment with the opening 20 in section 1. The section is also provided in its outer surface with a socket or recess 29 adjacent the inner end of the recess 4, and the section 1 is provided with a similar socket or recess 30 in the recess 3 adjacent the opposite end from the opening 18. Both the recesses or sockets 29 and 30 are provided with an enlarged counter-recess 31 of less depth than the recesses 29 and 30. The outer surface of each section is also provided with longitudinal curved grooves 32 and 33 leading to the recesses 3 and 4 for passage of the lead wires connected with the binding post screws mounted in these recesses, as will presently be described.

Referring first to Figs. 3 to 12, the parts and arrangement thereof for the pull type switch are shown in these figures. This comprises a stationary switch contact 34 of a sector shape as shown in Fig. 12, seated on the inclined step 9 of the circular recess 8 of section 1, and includes a circular perforated ear or lug 35 in the rounded end portion of the recess 17 where it is connected by a hollow rivet 36 (Fig. 5) in the opening 18, and connecting this contact with a binding screw plate 37 mounted in the recess 3 in the outer surface of this section and conforming generally to the shape of the recess 3 so that it is firmly held in position with this recess. This plate carries the usual binding post screw 38 for connecting one of the lead wires to the plate 37, and the inner end of the screw may extend into the socket 30 for clearance. This rivet 36 serves to secure both the plate 37 and the contact 34 to the housing, and also provides an electrical connection between them. The other stationary switch contact 39 also comprises a curved sector which is seated on the inclined surface 10 of the curved recess 8 opposite contact 34, and it is connected by the intermediate portion 40 with a central socket contact 41, below or outside the lower end of the housing within the screw shell contact 42, the connecting portion 40 being seated in and passing through the slot formed by the passages 19 and 19a. The rotary or movable switch contact is shown at 43 in Figs. 7 and 9 and comprises a circular body portion 44 at the diametrically opposite sides of which are laterally bent contact arms 45 terminating in inclined sector-shaped contacts 46. At the opposite side from these contacts 46 and intermediate them on the outer edges of the circular portion 44 are upwardly turned ratchet lugs 47, and the plate has a central opening 48 for mounting on a pivot pin 49 embraced by a coil spring 50, one end of which is held by a lug 51 under the noncircular head 52, which is also provided with a transverse slot 53 whereby it may be turned with a screwdriver for adjust-

ing the tension of the spring 50. The opposite end of the spring is extended laterally from the pivot pin and is bent laterally at 54 to seat in a notch 55 in an oscillatory insulating ratchet plate 56. This plate is also provided with ratchet openings 57, there being four arranged at 90 degrees apart and on diametrically opposite sides of the central pivot opening 58, whereby it is mounted for oscillating movements of the pin 49. One side of this ratchet plate has an extension forming a hook 59 for connection of a perforated link 60, which has an elongated opening 61 (Fig. 3) seating over the hook 59, and at its opposite end has a socket 62 to receive a ball on the end of a flexible pull chain 63. This chain passes through a guide sleeve 64 seated in the passage formed by the guide passages 6 and 6a, and which is flared at its opposite ends 65 and 66 to retain it in the passage and also guide the chain as it moves through this guide sleeve in the operation of the switch.

When assembled the ratchet plate 56 and the movable contact 43 are mounted on the pivot pin or stud 49 with the end 54 of the spring seated in the notch 55 and the contacts 46 on the inclined steps or sectors of the circular recess 8. The free end of the pivot stud or pin 49 is held in the opening 15 of section 1 while its noncircular head 52 is seated in the noncircular recess 23 in the section 2, as shown in Fig. 5. In this position the spring 50 is compressed longitudinally so that it retains the head 52 in this recess, but the pin may be slid inwardly to the left as viewed in Fig. 5 by a screw-driver inserted through the opening 24 to free the head from the socket or recess 23 and permit it to be rotated by means of the screw-driver to properly torsionally stress the spring 50 so that it tends to return the ratchet plate 56 to the normal or retracted position of Fig. 4. The movement to this position is limited by an enlarged ball 63a mounted in the pull chain and of larger diameter than the passage through the guide sleeve 64 so as to limit the inward movement of this chain by seating in the outer end of the sleeve. An outward pull on the chain will turn the plate 56 to the left, or counterclockwise as viewed in Fig. 4, and by engagement of the upwardly bent ears or lugs 47 on the movable switch contact 43 engaging alternately in the sector shaped openings 57 of the plate 56 will rotate the contact 43 a quarter revolution on each pull of the chain with a step by step movement. When the chain is released, the plate 56 returns to its normal position of Fig. 4 by action of the spring 50, the plate 56 moving sufficiently to the right as viewed in Fig. 5 to slide over the tops of the lugs 47 against the pressure of the spring 50, so that these lugs may enter the next set of openings 57 for the next of the step by step movements. It will be clear that in one position the contact feet or sectors 46 bridge the two stationary contacts 34 and 39 to close the circuit, and in the next or intermediate position they rest on the inclined surfaces 11 and 12 to break or open the circuit. Reverse movement of this contact 43 with the reverse movement of the operating ratchet plate 56 is prevented by the ends of contacts 46 engaging the stepped shoulders 13.

The screw shell contact 42 which receives and engages the outer lamp contact while the center lamp contact is in engagement with the center contact 41, is secured against the lower end of the housing by means of a transverse screw 67 which passes through the aligned openings 29 and 29a of the housing section. This screw shell has

an inwardly extending flange 68 resting against the end of the housing, and spaced upwardly extending ears 69 which are seated in the recess 21 and the outer end of the recess 4 in the sections 1 and 2. The head of the screw 67 rests against one of these ears 69 and the other end passes through the opening 70 in the other ear and is threaded into a tapped opening in a second binding screw plate 71 seated in the recess 10 4 of section 1. This screw 67 thus secures the plate 71 in the recess in the housing, secures the screw shell 42 to the housing, and also forms an electrical connection from the screw shell contact to the binding screw plate 71 which, as this 15 plate carries a second binding screw 72 by means of which the other lead may be connected to the plate, completes the circuit to the socket. The lower end portions of the two housing sections 1 and 2 are provided with a rectangular raised portion or boss 73 which seats in a similarly shaped recess 74 in the end flange 68 of the screw shell to assist in positioning and retaining this shell in position on the end of the housing.

The parts of a key type switch assembled in 25 the same housing or insulating body are shown in Figs. 15 to 19. The two stationary switch contacts are shown at 75 and 76. Contacts 76 comprises a contact portion 77 including laterally bent end portions 78 connected by an intermediate curved portion 79 with a mounting lug or ear 80 seated in the recess 17 in the housing section 1. This ear is perforated and is connected by a hollow rivet 36 passing through the opening 18 with the binding screw plate 37 mounted in the recess 3 in the outer surface of this section, the same as is the contact 34 of the pull type mounted in the section and secured to the plate. This rivet forms an electrical connection between the binding screw plate 37 and the contact 76 and secures both of them to the housing section, and when the contact 76 is mounted in this position the free contact portion 77 is located in the recesses 5 and 5a at one side of the guide passage formed by the passages 6 and 6a. The other stationary switch contact 75 comprises an intermediate reversely curved portion 81 and 30 82 terminating in a cross-shaped contact portion 83 with an end lug 84 and a connecting portion 84 for securing the central socket contact 85. This contact element is mounted in the housing with the portion 84 in the slot formed by the openings 19 and 19a, the curved portion 81 being extended around the bosses 28b, and with the lug 83 seated in the recesses 28 and 28a and against the shoulders 27 and 27a to locate the contact 82 in the recesses 5 and 5a opposite the contact 77. The reversely curved portion 82 is seated under the lugs 28 to retain this contact in position, and as the portion 84 extends through the slot 19, 19a the central contact portion 85 is outside the end of the housing and is located within the screw shell 42. This shell is fastened to the end of the housing the same as with the pull type by means of transverse screw 67 passing through the ears 69 on the shell and threaded into the other binding screw plate 71, as shown in Figs. 1 and 14.

The movable switch contact comprises an oblong cupped member 87 mounted on the stem 88 of the insulating operating key 89 provided with a winged head 90 forming a finger grip. The shaft 88 passes through an opening in the bottom wall of the contact 87 and is provided with lugs 91 located within the cupped contact which provide means forming a lost motion connection

between the key stem 88 and the contact 87. When assembled in the housing this contact is located in the recesses 5 and 5a between the switch contacts 77 and 82, the opposite or free end of the stem 88 being mounted in a bearing member 92 seated in the recesses 7 and 7a. At the other end it is provided with a reduced neck 93 having a bearing in the guide passages 6 and 6a. Turning of the key 89 will rotate the contact 87 by means of the lugs 91 so that its opposite ends bridge the two contacts 77 and 82, as shown in Figs. 13 and 14, to close the circuit, or shift it to an intermediate position at right angles to this position to open the circuit. The two contact elements 75 and 76 are spring contact elements so that normally when the movable contact 87 turns to the intermediate or right angle position, or that of Figs. 13 and 14, the contact portions 77 and 82 are somewhat closer together than the length of the contact 87, so that when it is turned to the "on" or bridging position the contacts 77 and 82 are forced apart somewhat against the resilient action of these contact elements, to thus make a good electrical contact when the switch is closed. When it is turned from the "on" or bridging position to the intermediate position, the lost motion connection provided by the lugs 91 in the copper member permits a quick break of the circuit under the resilient action of the stationary contacts.

It will be seen from the above that with the same housing or body, either a key type or a pull type switch may be assembled in it without changing this housing in any way. The same binding screw plates 37 and 71 are used with both types of switches and they are both mounted in the same way, the plates 37 being connected to one of the stationary switch contacts of either type of switch within the housing by the hollow rivet 36 passing through an opening in the section 1. The central socket contact, either 41 or 85, is mounted by connecting portions located in the outlet slot 19, 19a in one end of the housing, and each is connected to the other stationary switch contact in that particular type of switch. The screw shell contact 42 is secured to the housing and electrically connected to the other binding screw plate 71 by the same means with both types of switches, that is, by transverse screw 67, and this screw also secures the binding screw plate 71 to the housing in both types of switches. Therefore, certain parts of the housing and certain switch parts and contacts are used with both types of switches, and substantially the only different parts are the movable switch contacts and the operating means therefor. The operating means for both types extends from the housing through the guide passages 6 and 6a. Therefore, in this construction only one set of dies is re-

quired for molding the housing sections for mounting either a key or pull type switch, and a relatively large proportion of the parts can be used for both types of switches.

It is to be understood that the device as shown assembled in the drawing will be enclosed in the usual metal shell and paper or fiber insulating lining (not shown), these parts being omitted to simplify the drawing.

Having thus set forth the nature of my invention, I claim:

In a lamp socket and switch of the character described, an insulating hollow body comprising a pair of sections having longitudinally arranged opposed contacting surfaces, each section being provided with a separate recess in its outer surface adapted to seat a binding screw plate, one of said sections being provided with a recess on its inner side opposite the outer recess and an opening through the wall of the section connecting said recesses, said section also provided with a circular recess adjacent the first inner recess provided with a stepped inclined surface adapted for mounting spaced stationary contacts and an elongated longitudinal recess spaced laterally at one side of the circular recess, the other section being provided with a similar recess opposed to said elongated recess providing therewith a compartment adapted for containing a pair of switch contacts, said sections being provided with a circular passage in their opposed surfaces leading through the side wall of the body to said elongated recesses adapted for mounting a switch operating means, said sections being provided with aligned slots in their opposed surfaces extending through one end of the body to the interior thereof adapted for mounting a central lamp socket contact, said sections further being provided with aligned openings central with the circular recess adapted for mounting a support for a rotary switch contact, and said sections being also provided with aligned openings extending transversely therethrough from the recess in the outer surface of the second section adapted to receive a securing screw for a screw shell contact.

HARVEY HUBBELL.
